UNITED STATES PATENT OFFICE.

ROBERT SCHLEMM, OF CHICAGO, ILLINOIS.

AUTOMATIC VENDING-MACHINE.

SPECIFICATION forming part of Letters Patent No. 758,110, dated April 26, 1904.

Application filed June 19, 1903. Serial No. 162,161. (No model.)

To all whom it may concern:

Be it known that I, ROBERT SCHLEMM, a citizen of the United States, residing at Chicago, in the county of Cook and State of Illinois, have invented certain new and useful Improvements in Automatic Vending - Machines, of which the following is a specification.

This invention relates to coin-controlled automatic vending apparatus, and the particular objects of the improvements embodied therein are the production of an apparatus of comparatively simple construction whereby it may be cheaply constructed and will not be liable to get out of order from the manipulations and abuse to which such machines are ordinarily subjected; the production of a machine of this class in which the articles vended may be placed therein without special or orderly arrangement and in large quantities and which will deliver the articles singly and with certainty; to provide means for manipulating a sounding device, said means at the same time causing the delivery of the article vended, and to produce an apparatus having generally objects of utility and desirability not possessed by other machines of the same class.

In the accompanying drawings, which form a part of this application, Figure 1 is a perspective view of my apparatus complete. Fig. 2 is a top plan view, on an enlarged scale, with the cover removed. Fig. 3 is a top plan view of the coin - controlled and actuating mechanism. Fig. 4 is a vertical section on the line 4-4 of Fig. 5; and Fig. 5 is a view, partly in front elevation and partly in vertical section, showing the interior of the machine.

Referring to the details of the drawings, A represents a box made of sheet metal and having a base a' , sides a^2 , and a top a^3 , which may be connected together in any suitable manner, whereby authorized access may be had to the interior mechanism, the container, and the coin box or receiver. Surmounting the box A is the figure of a sitting hen, as B, which is also preferably made of metal and is rigidly secured to the top of the box. In the front side of the box is a coin-slot a^4 , and near the base is an opening through which projects a delivery trough or cup C, which is made of

metal and has its rear portion c' extending inwardly and upwardly toward the center of the apparatus for the purpose of receiving the articles vended. In this instance the articles vended are artificial eggs and same are indicated by dotted lines in Fig. 4 and will be 55 hereinafter referred to as "eggs."

Extending across the lower portion of the box A and spaced above the base a' , so as to form substantially a false bottom for the box, is an iron plate D, which is supported from the base in any suitable manner and in turn supports the operative parts of the device. The space between the base and the plate D is in part utilized by the coin-box E, the trough C, and a noise-producing device or "squawker" F, the latter being of the well-known bellows type and adapted to produce sounds in imitation of the cackling of a hen. Arranged on the plate D are the parts which through the medium of the coin and the manually-operated lever, as 60 will be set forth in detail, cause the eggs to be delivered from the hopper to the delivery-trough. Said parts are as follows: A cast-metal plate G of the irregular contour shown is pivotally mounted on the central portion 65 of the plate D. Said plate G is formed with a tapering extension g' with a cut-out portion g^2 , which forms shoulders g^3 and g^4 at opposite ends thereof, with a rounded lug g^5 , a cut-under portion g^6 , a straight edge g^7 , and a 70 hook g^8 , said edge and hook being on an overhanging portion g^9 , while g^{10} represents the pivot on which said plate is mounted. To the upper side of the cut-under portion g^6 is secured one end of a coil-spring H, the opposite 75 end of which is attached to a set-screw h' , which is fixed to the plate G. Secured to the upper side of the plate G near the shoulder g^3 is the lever J, the forward portion of which projects through an opening provided therefor in the front side of the box and terminates in a ring j' , and the rear end terminates in a downwardly-turned hook j^2 . The 80 central portion of the plate G is cut out and within the space thus left is placed a wheel K, in the periphery of which are formed series of teeth k' and from the upper surface of which extend fixed pins k^2 . In the center of the

85

90

95

- wheel is secured a shaft or rod L, which is adapted to rotate with the wheel and is provided with a suitable bearing in the top of the box to maintain it in a vertical position and prevent lateral movements. Mounted on the plate D is a pawl k^3 , the point of which is normally held in engagement with the periphery of the wheel by a spring k^4 , secured to a screw k^5 , as clearly shown in Fig. 3.
- Near the extension g' of the plate G on a pivot m' is mounted a lever M, the forward and short arm of which terminates in a hook m^2 , and the rear portion of which is formed with an angular shoulder m^3 and terminates in an angular portion m^4 . Near the lever M is a second lever N, which is pivotally mounted on the pin n' , has its forward portion terminating in a hook n^2 and its rear portion curved and terminating in a rounded portion n^3 . The relative positions of the levers M and N are fixed when the parts are at rest by a two-arm spring O, secured to a pin o' , fixed in the plate D and having one arm secured loosely in a lug n^4 on the upper side of the lever N and the other arm similarly secured in a lug m^5 on the upper side of the lever M, all as clearly indicated in Fig. 3, in which the parts are shown at rest. Secured to the plate D at a point between the forward arms of the levers M and N is a post P, which serves primarily as a support for the coin-chute R, but which also serves to limit the movement of the lever M toward the lever N, and hence maintains a fixed distance between the respective hooks of said levers.
- Pivotedly mounted on the plate G is an arm S, having a hooked portion s' , adapted to engage successively the vertical pins k^2 on the wheel K as the latter is rotated and to prevent the reverse rotation of said wheel. A wire spring s^2 , having one end secured to the lever J and its other end attached loosely to a lug on the upper side of the arm S, holds the latter in constant engagement with said pins.
- When a coin is held between the hooks m^2 n^2 , the operation of the above-described mechanism is as follows: The depositor of the coin pulls outwardly or in the direction indicated by the arrow the lever J, whereupon the plate G is caused to turn upon its pivot g^1 in the direction indicated by arrows, thus causing the lug g^5 to bear against the rounded end of the lever N, moving the curved arm of same outwardly and causing a corresponding inward movement of the forward arm of said lever, which in turn presses the coin against the end of the forward arm of the lever M. As the forward end of the lever M moves away from the post P the rear end m^4 of said lever moves in the opposite direction, thus clearing the shoulder g^3 of the plate G and permitting the latter to turn upon its axis the full limit of the forward movement of the lever or rod J. The arm S moves with the plate G, and its hook

s' , being in engagement with one of the pins k^2 of the wheel K, causes the latter to be partially rotated, and hence turns the post or shaft L. When the operator releases the lever J, the spring H, acting upon the plate G, returns the parts to their initial positions, it being understood that the coin has dropped from between the hooked ends of the levers M N by reason of the spreading apart of the latter. The pawl k^3 by engaging the teeth k^1 prevents the reverse movement of the wheel. Hence another pin k^2 is brought into operative relation with the hooked arm S in a manner clearly indicated by the drawings. In the forward or outward movement of the lever J, above described, the hooked end j^2 , which is in engagement with an extension f' of the bellows of the squawker F, inflates said bellows, thus drawing in the air, the immediately following emission of which causes the desired cackling noise, it being understood that the collapse of the bellows is permitted by the return of the lever J to its initial position.

Supported above the plate D is a circular pan T, in the bottom and side of which is an opening t' , which communicates with the rear portion c' of the trough C. Arranged in the pan T and secured on the shaft L by a collar and set-screw t^2 is an egg-receiver t^2 , which is subdivided into a series of compartments t^3 , each of which is just large enough to receive but one egg at a time. This receiver is without top or bottom and serves as a continuation or extension of the hopper V, the lower portion of which registers with the said receiver. The hopper is supported on posts v^2 and at the portion directly over the opening t' in the pan T is provided with an apron v' , which serves to prevent any of the eggs from falling directly from the hopper through said opening into the trough without first traversing the compartments of the receiver. It will be seen that as the shaft L is turned in the manner heretofore set forth the receiver is partially rotated, so that one of the compartments in the latter is brought directly over the opening t' and the entrance of the trough, thus permitting the egg in said compartment to fall by gravity into the trough. The eggs are simply poured into the hopper and are fed by gravity into the compartments t^3 , the sides of the hopper being inclined downwardly and converging, so that the bottom of the hopper extends slightly over the outer edge of the receiver.

The coin-chute R is placed directly over the coin-box E and is of the usual or well-known construction.

It will be understood that as the plate G returns to its original position the shoulder g^4 strikes against the adjacent rounded portion of the lever M and thereby throws outwardly the forward end of said lever, thus releasing the coin, which up to that time has been held between the notches or jaws m^2 n^2 .

Having thus described my invention, what

I claim as new, and desire to obtain by Letters Patent, is—

to hold by frictional engagement a coin, and having their other ends normally in engagement with portions of the said plate. 25

3. In a vending-machine, a rotatably-mounted wheel having inclined teeth in its periphery, means engaging said teeth to prevent the rotation of the wheel in but one direction, a 30 pivotally-mounted plate adapted to rotate the said wheel and provided with shoulders, a lever secured to said plate and manually operated, levers pivotally mounted, and having portions engaging the shoulders on said plate 35 to prevent the movement of the latter, said levers having other portions adapted to receive and hold a coin in frictional engagement, and means for returning the plate to its normal position. 40

In testimony whereof I affix my signature in presence of two witnesses.

ROBERT SCHLEMM.
